UNITED STATES PATENT OFFICE.

KI WILLIAMS, OF CARNEYS POINT, AND HERBERT W. DAUDT, OF PENNS GROVE, NEW JERSEY, ASSIGNORS TO E. I. DU PONT DE NEMOURS & COMPANY, OF WILMINGTON, DELAWARE, A CORPORATION OF DELAWARE.

PROCESS OF SYNTHESIZING LEAD TETRA-ALKYLS.

No Drawing.

Application filed August 9, 1924. Serial No. 731,060.

To all whom it may concern:

Be it known that we, KI WILLIAMS, a citizen of the United States, and a resident of Carneys Point, in the county of Salem and State of New Jersey, and HERBERT W. DAUDT, a citizen of the United States, and a resident of Penns Grove, in the county of Salem and State of New Jersey, have invented a certain new and useful Process of 10 Synthesizing Lead Tetra-Alkyls, of which the following is a specification.

This invention relates to the production of lead tetra-alkyls by the interaction of metallic lead and an alkyl bromide in the presence of a reducing agent and of a catalyst, and comprises mixing a solution of a strong base—for example, an alkali-metal hydroxide—with the reaction mass resulting from said interaction, and then proceeding 15 in the usual way to remove excess alkyl bromide and distill off the tetra-alkyl lead. By this intermediate addition of a strong alkali, the yield of tetra-alkyl lead is substantially increased.

20 Alkaline solutions of the kind indicated above can be used to advantage in the treatment of reaction masses obtained in various ways from lead and an alkyl bromide. Thus, reaction masses to which the aforesaid solutions may advantageously be added may be produced in accordance with processes described in co-pending applications of William S. Calcott, Ser. No. 592,598, filed October 5, 1922; William S. Calcott and H. W. 25 Daudt, Ser. No. 594,583, filed October 14, 1922, and K. P. Monroe, Ser. Nos. 596,514, 707,581, and 729,046, filed October 23, 1922, April 19, 1924 and July 30, 1924, respectively. The increased yield resulting from the 30 above-described treatment is believed to be due to the presence, in the reaction mixtures above referred to, of a substantial proportion of hexa-alkyl-di-plumbane (Pb_2Alk_8), which is converted by this special treatment 35 into a tetra-alkyl lead. The conversion of other intermediate products to tetra-ethyl lead and the disintegration of the sludge may also contribute to the increase in yield. The latter factor also allows an easy transfer of the reaction mass from one piece of 40 equipment to another.

Our new process may be illustrated by the following example:

100 parts of lead-sodium alloy containing 14.3% sodium, 85 parts of ethyl bromide, 8 parts of ethyl cyanide, 0.4 parts of water, and 2 parts of pyridine are placed in a steel tube which is then closed and rotated for 55 about 8 hours in an oil bath maintained at 83–85° C. The tube is then opened and to 60 the reaction mass therein, there are added 115 parts of 6% sodium hydroxide solution—the sodium hydroxide solution being equal in weight to eight times the active sodium contained in the alloy used. The resulting mixture is digested at a temperature of 65 50° C. for 5 hours, and then heated to distill off first excess ethyl bromide and finally tetra-ethyl lead.

Instead of sodium hydroxide, potassium 70 hydroxide may be used in the above example.

We claim:

1. In the process of producing lead tetra-alkyls by the interaction of lead and an 75 alkyl bromide in the presence of a reducing agent and a catalyst, the step which comprises mixing with the reaction mass resulting from said interaction, a solution of a strong base.

2. A process as set forth in claim 1 in which, after mixing the reaction mass with the solution of a strong base, the resulting mixture is digested and then heated to distill off first excess alkyl bromide and then 85 tetra-alkyl lead.

3. In the process of producing tetra-ethyl lead by the interaction of a lead-sodium alloy having approximately the composition indicated by the formula $PbNa_2$, with ethyl bromide and a neutral hydroxylic compound capable of reacting with sodium to form hydrogen, in the presence of a catalyst, the step which comprises mixing water and an alkali-metal hydroxide with the reaction mass resulting from said interaction.

4. A process as defined in claim 3 in which the mixture obtained by mixing water and an alkali with the reaction mass is digested for about 5 hours at a temperature of about 50° C., and subjected to distillation to drive off first ethyl bromide and then tetra-ethyl lead.

5. A process as defined in claim 3 in which the alkali-metal hydroxide is sodium hydroxide.

6. A process as defined in claim 1 in which the solution of a strong base is a 6% sodium hydroxide solution. about equal in weight to eight times the active sodium contained in the alloy used.

In testimony whereof we affix our signatures.

7. A process as defined in claim 3 in which the water and alkali-metal hydroxide are so proportioned as to form a 6% solution, and the amount of such solution used is
